UNITED STATES PATENT OFFICE.

MORRIS BERNHARD, OF NEW YORK, N. Y., ASSIGNOR TO DREYFUS BROTHERS, OF SAME PLACE.

DESIGN FOR A PENDANT.

SPECIFICATION forming part of Design No. 15,109, dated July 1, 1884.

Application filed April 25, 1884. Term of patent 7 years.

To all whom it may concern:

Be it known that I, MORRIS BERNHARD, of the city, county, and State of New York, have produced a new and original Design for Pendants, of which the following is a full, clear, and exact description.

Reference is to be had to the accompanying drawing, forming part of this specification, in which a face view of my newly-designed pendant is shown.

In my newly-designed pendant a crescent-shaped piece, A, has its ends held on the ends of a cross-piece, B, which piece A gradually increases in diameter or thickness from the ends toward the middle. Tufts C are formed on the ends of the cross-piece B. A tuft, D, is formed on the top of the cross-piece B, at the center, and at the said tuft a loop, E, is secured to the cross-piece. A tuft, F, or ball is suspended from the middle of the cross-piece B by means of a cord, G. The cross-piece B increases in diameter from the middle toward the ends, and is provided with spiral grooves H, in which a cord or filament, J, is placed.

Having thus described my invention, I claim as new and desire to secure by Letters Patent—

1. The herein-described newly-designed pendant, consisting of a crescent-shaped pendant suspended from a cross-piece, the diameter of which increases from the middle toward the ends, substantially as set forth.

2. The herein-described newly-designed pendant, consisting of a crescent-shaped pendant suspended from a cross-piece, provided at each end with a tuft, and increasing in diameter from the middle toward the end, substantially as set forth.

3. The herein-described newly-designed pendant, consisting of a crescent-shaped pendant, suspended from a cross-piece having spiral grooves, substantially as set forth.

4. The herein-described newly-designed pendant, consisting of a crescent-shaped pendant, suspended from a cross-piece having spiral grooves, in which cords or filaments are placed, substantially as herein shown and described.

MORRIS BERNHARD.
